United States Patent Office.

JONATHAN DEARBORN, OF SEABROOK, NEW HAMPSHIRE.

Letters Patent No. 64,204, dated April 30, 1867.

IMPROVEMENT IN MECHANICAL TELEGRAPHS.

The Schedule referred to in these Letters Patent and making part of the same.

TO ALL PERSONS TO WHOM THESE PRESENTS SHALL COME:

Be it known that I, JONATHAN DEARBORN, of Seabrook, in the county of Rockingham, and State of New Hampshire, have made a new and useful invention having reference to Telegraphic or Other Purposes; and I do hereby declare the same to be fully described in the following specification, and represented in the accompanying drawings, of which—

Figure 1 is a top view.

Figure 2, a side elevation; and

Figure 3, a vertical and longitudinal section of it.

Figure 4 is a horizontal section, taken through its connection racks.

In such drawings, A and B are two horizontal shafts, each of which has three bell-crank, *a b c*, each of which is arranged so as to stand at an angle of one hundred and twenty degrees with respect to that next to it. The cranks of one shaft are connected with those of the other by means of three rods *d e f*, each of which embraces one of the cranks of one shaft and one of the cranks of the other, the same being as represented in the drawings. One or more sprocket or lantern-wheels is fixed on each of the shafts A B, and concentrically therewith. Endless chains *D D'* go around the wheels *C C* of the two shafts, and two other such wheels, *E E*, fixed on two other horizontal shafts, *G G*, arranged underneath the shafts A B. The link *g* of each of the said chains has a trapezoidal-shaped flange projecting inward from one edge of it, the same being to enter between the cross-bars of the sprocket-wheel, and prevent the chain from slipping around on the wheel. Each link also has one of a series of letters of the alphabet fixed to it, or to a block, *i*, fixed to the link.

When two endless chains are so made, viz, with letters or figures on their links, each chain having its letters or figures to correspond with those of the other, and the two chains have the same number of links in each, and the shafts of the upper sprocket-wheels of the two chains are provided with bell-cranks, connected by connecting-rods, as described, the apparatus or machinery can be used for telegraphic purposes.

The mode of connecting the two shafts of the upper sprocket-wheels, viz, by six bell-cranks and three connecting-rods, as described, enables the two shafts to be placed at a very great distance apart, and to be revolved synchronously whenever either of them is put in revolution by manual power applied to it. Now, when one of these chains is revolved so as to bring either of its letters against a fixed mark, a like letter of the other chain may be brought, at the same time, against another fixed mark, whereby an observer might, by observing the mark and letter, determine what letter his fellow-telegrapher may bring up to his own fixed mark. In this way a system of telegraphic signals may be made between the two, from one to the other and back.

In order to transmit rotary motion from one of the lower shafts of the chains, such shaft may have two bell-cranks *m n* on it. From these cranks connecting-rods *o o* may proceed to and be jointed to two serrated racks *H I*, arranged over and on a sprocket-wheel, *K*, and connected by a chain or band, *L*, going around a pulley, *M*, the whole being as shown in the figures. While the shaft provided with the two cranks may be in revolution, a reciprocating movement will be imparted to the two racks, whereby they will be caused, by their action on the sprocket-wheel *K*, to put such wheel in revolution in one direction, with a continuous motion, such wheel being mounted on a shaft, *S*.

What I claim as my invention in the above-described mechanism is as follows:

I claim the combination and arrangement of the six bell-cranks and the three connecting-rods with the two shafts, and also with the two telegraphic endless chains and their sprocket-wheels, applied together and constructed substantially in manner and so as to operate as specified.

I also claim the combination and arrangement of the two serrated racks *H I* (connected by a chain going around a pulley, as described) with the sprocket-wheel *K*, the connecting-rods *o o*, and bell-cranks *m n*, applied to a rotary shaft as set forth.

JONATHAN DEARBORN.
